FRANK S. HERETH, OF NEW YORK, N. Y., ASSIGNOR TO E. R. SQUIBB & SONS, A CORPORATION OF NEW YORK.

COMBINED BOTTLE AND DROPPING DEVICE.

1,142,517.

Specification of Letters Patent.

Patented June 8, 1915.

Application filed July 21, 1913. Serial No. 780,105.

To all whom it may concern:

Be it known that I, FRANK S. HERETH, a citizen of the United States, residing at the city of New York, in the borough of Brooklyn and State of New York, have invented certain new and useful Improvements in Combined Bottles and Dropping Devices, of which the following is a full, clear, and exact description.

10 The invention resides in a combined bottle and dropping device, particularly adapted for use with liquids, such as medicinal compounds, chemical re-agents, and the like.

The object of the invention is to provide 15 a bottle and a self contained dropping device therein, the two being so proportioned and arranged that the liquid may be forced in drops from the mouth of the bottle by the internal pressure created by the dropping 20 device.

With this and other objects in view, my invention consists essentially of a bottle having a contracted mouth and a rod within the bottle extending therethrough, which rod 25 fits closely in the mouth of the bottle so that upon inward movement of the rod, a portion of the liquid will be displaced in drops if the bottle is tilted to permit the liquid therein to fill the neck of the bottle.

30 In the drawings, wherein like reference characters refer to like parts, Figure 1 is an elevation partly in section of my combined bottle and dropping device; Fig. 2 is a like view showing the bottle in tilted position and the rod partially extended; and Fig. 3 is a detail showing the cap for closing the bottle when not in use.

In the construction shown, a glass bottle 1, of a suitable capacity to hold the desired 40 amount of liquid, is provided with a relatively long and narrow neck 2.

Within the bottle is a solid rod 3, which is preferably of glass, although other substances may be used, depending upon the 45 liquid which it is desired to store in the bottle. The neck 2 of the bottle is provided with a mouth through which the liquid and rod are inserted and which may afterward be sealed as at 4 by heating the glass to 50 melting point thus providing a hermetic closure for the bottle.

The neck 2 is scratched or scarred to form a weakened portion 5 immediately below the sealed end 4. When it is desired to use the

contents of the bottle, the sealed end of the 55 neck may be broken off at the weakened portion 5, to form a mouth 6, the edges of which are relatively smooth. The weakened portion 5 also insures that the sealed end may be readily broken off without breaking 60 the end of the rod 3, which rod is of sufficient length to extend beyond the mouth 6, so that the end of the rod may be grasped by the user when it is desired to withdraw 65 a portion of the liquid from the bottle. The 70 rod 3 is preferably made of sufficient thickness to almost fill the mouth of the bottle to facilitate the forcing of the liquid from the bottle in drops. The neck and mouth are so proportioned that sufficient air will not be 75 admitted into the bottle to completely fill the space or vacuum left by the displacement of the air from the neck of the bottle in case the bottle is not completely filled when the 80 bottle is tilted to permit the liquid to fill the neck and mouth, the pressure of the atmosphere against the mouth 5 of the bottle being sufficient to retain the liquid within the bottle.

When it is desired to remove a portion of 80 the contents of the bottle, the solid rod 3 is first moved outwardly which may be done before or after the bottle has been turned to the tilted position. In either case, during this outward movement, air is admitted 85 to the bottle to fill the space or vacuum left by the displacement of the rod. The bottle then is tilted, if the same has not already been done, to permit the liquid to run into the neck of the bottle and close the mouth 90 6; the liquid within the neck of the bottle acting as a seal to prevent any more air from being admitted or exhausted from the bottle. The liquid, however, will not flow out of the 95 bottle, as the amount of air admitted by the outward movement of the rod does not exactly equalize the atmospheric pressure against the liquid in the mouth of the bottle. The rod 3 is afterward pushed inwardly and acts like a piston to compress the air trapped 100 within the bottle to slightly above atmospheric pressure. This increase of pressure is sufficient to force a portion of the liquid in the neck of the bottle out through the mouth in drops, the number of drops being 105 controlled by the contained inward movement of the rod. It is therefore evident that I have provided a dropping device which

remains permanently in the bottle and by its piston-like action in conjunction with the mouth of the bottle, any desired quantity of liquid may be withdrawn from the bottle in drops.

In Fig. 3 I have shown a cap 7 of rubber or the like, having one end closed as at 8, which may be used as a stopper for the bottle when the same is not in use.

10 While I have described my invention in connection with a specific form of bottle, it is to be understood that the invention is equally applicable to receptacles for liquids of all sizes and shapes, the essential feature 15 of the invention being that the receptacle be so proportioned that the liquid will remain within the bottle except when it is forced therefrom in drops by an internal pressure resulting from the inward movement of the 20 rod or dropping device.

While I have shown a solid rod adapted to slide through the mouth of the receptacle, yet it is evident that a piece of glass tubing sealed at one or both ends would serve the 25 same purpose as a solid rod, and the term "solid rod" as used in the annexed claims is deemed sufficiently broad to cover any rod which has no passage therein through which the liquid could be forced out of the 30 receptacle instead of between the mouth of the receptacle and the rod.

Having thus described my invention, I claim:—

1. A receptacle having a closed mouth and containing a smooth solid rod fitting loosely in the mouth of the receptacle, said rod being of slightly less cross sectional area than said mouth and extending into the body of the receptacle, said rod being adapted to slide through the mouth of the receptacle for the purpose set forth.

2. The combination with a receptacle having a contracted mouth, of a solid rod within said receptacle extending through said mouth, said rod being of slightly less cross-sectional area than the area of the mouth.

3. The combination with a bottle having a sealed neck and a weakened portion whereby the end of the neck may be broken off to form a mouth, a rod within said bottle extending into said neck, said rod extending beyond said weakened portion and being of slightly less cross-sectional area than the cross-sectional area of the neck at the weakened portion.

In witness whereof, I subscribe my signature, in the presence of two witnesses.

FRANK S. HERETH.
